East Pittsburgh, Pa., a corporation of Pennsylvania

Application August 19, 1944, Serial No. 550,249

4 Claims. (Cl. 114—24)

1

Our invention relates to gyroscopic control apparatus and more particularly to gyroscopic control apparatus for submersible crafts as to torpedoes.

The Government of the United States has been granted a certain royalty-free license for governmental purposes with respect to the invention herein described.

Gyroscopic control for steering a torpedo is well known but with the recent first fairly extensive use of electrically propelled torpedo some special problems called for solution.

One object of our invention is the provision of simple and reliable gyroscopic steering control apparatus for a torpedo.

Another object of our invention is the provision of clutching means for the drive of a gyro wheel interlocked with locking means for the rotating assembly which when unlocked provides three degrees of freedom with respect to rotation for the gyro wheel.

Another object of our invention is the provision for steering control that is substantially unaffected by vibration of the torpedo.

A still further object of our invention is the provision of automatic means responsive to the firing of a torpedo for stopping the gyro wheel drive motor, disengaging the gyro wheel from the drive motor, and releasing the gyro wheel that it has three degrees of freedom of rotation.

The foregoing objects expressly made are merely illustrative, and are not in the least to be taken as exhaustive statements of the objects and advantages of our invention. Many other objects and advantages will become more readily apparent from a study of the following specification and the appended claims when made in conjunction with the accompanying drawings, in which:

Figure 1 is a diagrammatic showing of the electrical control and a schematic showing of some of the mechanical elements coacting with the electric control;

Fig. 2 is a view from the aft region, with certain parts broken away at the left and at the top, showing our steering control gyro;

Fig. 3 is a side view, from the port side, of our control gyro, the case being broken away and some other parts being broken away to illustrate some details; and

Fig. 4 is a plan view of our control gyro.

To gain a better understanding of the details of our invention, a brief general discussion of gyroscopic steering of torpedoes and a study of the operation of the electrical equipment shown in Fig. 1 may be helpful.

In Fig. 1 we show a portion of a torpedo including the tail-cone 1, the afterbody 2, and a portion of the main section 3 of a torpedo. Since the torpedo is electrically propelled, we show a

2

battery B arranged to be connected to the torpedo propulsion motor M. The propulsion motor is, through shaft S and suitable transmission gears, coupled to the two propellers P to drive them, respectively, in opposite directions during propulsion of the torpedo. The motor M is also coupled to drive a "distance gear" 4 for operating a drum controller or other suitable switches 5 for effecting certain control functions, some of which constitute no part of our invention.

The torpedo, as is well known, is provided with horizontal rudders 6 for controlling the depth of operation of the torpedo and with vertical rudders 7 and 8 for controlling the course of the torpedo.

15 Our invention is primarily concerned with the control of the vertical rudders.

The vertical rudders are mechanically coupled to the armatures 9 and 10 which are in turn actuated by the solenoids 40 and 47. The gyro, or gyrostat, G, to effect proper steering of the torpedo toward the enemy target, controls the energization of solenoids 40 and 47.

Normally during transportation, the rotating assembly of gyro G is locked in fixed position on the torpedo and the gyro wheel 23 is in clutching engagement with the gyro motor GM. Just before the torpedo is fired, the gyro wheel is brought up to full speed by the gyro motor GM and the course for the torpedo is selected by so positioning the contact segments 29 and 30, having the relatively narrow spacer 31 of insulation between them, that the spacer 31 points in the direction required for the course setting selected.

Just before firing the switch 11 is closed whereupon a circuit is established from the upper terminal of the battery B through switch 11, conductor 12, through the gyro motor GM, conductor 13, contacts 14 of the gyro transfer switch 15 to the lower terminal of the battery.

Substantially at the same time switch 11 is closed, the course for the torpedo is set. The gyro wheel 23 attains full speed in a relatively short time whereupon the torpedo is fired.

The instant the torpedo is fired the trigger lever T actuated by the dog D closes the switch 16 to thus establish a circuit from the positively energized conductor 12 through switch 16, coil 17 of the clutching mechanism 18 to the negatively energized conductor 13.

50 Energization of coil, or solenoid, 17 actuates the armature 19 toward the right thus moving the lever 20 pivoted at 21 clockwise to thus cause the clutch 22 to release its driving connection between the gyro motor GM and the gyro wheel. The clockwise movement of the lever 20 releases the spring biased levers 24 and 25 so that they move clockwise and counterclockwise, respectively. Counterclockwise movement of lever 25 releases the spring biased gyro transfer switch 15 so that this switch opens its contacts 14 and

closes its contacts 28. Opening of contacts 14 effects deenergization of both the gyro motor GM and the coil 17, both of which at this stage being no longer needed.

Closure of contacts 28 establishes a circuit from the positive terminal through the actuating coil of contactor 27 and contacts 28 to the negative terminal of the battery B. Operation of contactor 27 causes the closure of contacts 26 to thus connect the propulsion motor M to the battery to propel the torpedo through the water.

To effect proper steering of the torpedo toward the target the contact segments 29 and 30, having the relatively narrow strip of insulation 31 between them, are so positioned that the strip 31 holds a given position with reference to the target. The given position nearly always means that the strip 31 points toward the target; it thus indicates the direction the torpedo is to take to arrive at, or hit, the target. For all torpedo shots except one directly at the target the small contact roller 32 will be in contact with either segment 29 or segment 30, depending on the direction of the target with reference to the torpedo tube.

Assuming that the target is to the left of the longitudinal axis of the torpedo as it is fired, then the small roller 32, making substantially point contact, will be in contact with segment 30. This means a circuit is established from the positive terminal of the battery through contacts 33, potentiometer resistor 34, conductor 35, terminal contact arms 90, 91, and 92 coupled to rotate with the outer gimbal ring 70 of the gyro, roller 32, segment 30, actuating coil 36 of the steering control relay 37 back to the junction between the potentiometer resistor and contacts 33.

The circuit traced will cause operation of the relay 37 to close its contacts 38. Closure of contacts 38 establishes a circuit from the positive terminal of the battery through contacts 26 and 38, conductor 39, solenoid or coil 40 for actuating the armature 10, and conductor 41 to the negative terminal of the battery.

The rudders 7 and 8 are thus deflected so as to turn, or steer, the torpedo toward the left. This deflection of the rudders continues until the torpedo has moved to the left sufficiently so that the roller 32 comes into contact with the strip of insulation 31. When this happens the direct circuit for coil 36 of the relay 37 is interrupted at the roller and it is connected in series with resistor 42.

Resistor 42 has a relatively high resistance value to thus decrease the energization of coil 36 sufficiently so that the contacts 38 are opened. The result is that the rudder deflection immediately ends and the rudders take a position falling substantially in a vertical plane including the longitudinal axis of the torpedo.

In order that the control operation or effect of the gyro may be invariable and be immediately effective in proper magnitude the potentiometer resistor is connected to the battery when the torpedo boat arrives at the battle station. The circuit for the potentiometer resistor 34 may be traced from the positive terminal of the battery through the contacts 33, potentiometer resistor 34, back to the negative terminal of the battery.

The actuating coil 36 is connected in series with the resistor 42 and segment 30 across the left-hand half of resistor 34. The actuating coil 43 is similarly in series circuit with resistor 48 and segment 29 connected across the left-hand half

of resistor 34. The resistance values of resistors 42 and 48 are so chosen that the coils 36 and 43 and the resistors 42 and 48 are at a stable temperature. The coils 36 and 43 thus, when called upon to control the rudders, are already heated and thus produce invariable control effect.

Further, the segments 29 and 30 are during transportation of the torpedo so adjusted that the roller 32 makes contact with the strip 31 only. Coils 36 and 43 are thus energized an equal relatively small amount. The energization is just sufficient to produce the heating effect mentioned but insufficient to cause actuation of the relays 37 and 44.

It is, of course, apparent that the control effect hereinbefore discussed is not "dead beat" and in consequence there is some tendency, at least on the first approach of the torpedo to a position such that roller 32 falls on the strip 31, for the torpedo to move beyond the required direction.

As the torpedo moves beyond the desired direction the roller 32 makes contact with segment 29 whereupon coil 43 of relay 44 is directly and fully energized and this relay closes its contacts 45. Closure of contacts 45 establishes a circuit from the positive terminal of the battery through contacts 26 and 45, conductor 46, coil or solenoid 47 for actuating armature 9, to the negatively energized conductor 41. The rudders 7 and 8 are again actuated to bring the torpedo back on the course.

After a few possibly rapid and possible aperiodic hunting cycles the torpedo takes a steady substantially direct course toward the target. What hunting there is after a steady state is obtained is not great and is periodic and thus does in no way harmfully affect the course of the torpedo.

If the torpedo has moved beyond the target as determined by the range setting of the distance gear 4 without making a hit the controller 5 will establish a circuit from the positive terminal of the battery through contacts 26, conductor 49, segment 50, conductor 51, actuating coil 52 of the spiralling relay 53, to the negative terminal of the battery.

Operation of the spiralling relay opens the contacts 33, thus disconnecting the gyroscopic control, and closes the contacts 54. A circuit is thus established from the positive terminal of the battery through contacts 54, resistor 55, conductor 46, solenoid 47, and conductor 41 back to the negative terminal of the battery.

This energization of the solenoid 47, through armature 9 operates the rudders 7 and 8 hard over to one side, and in consequence the torpedo begins to move in a spiral seeking the target it failed to hit.

In the absence of resistor 55 the torpedo might move in circles but the characteristics of resistor 55 are so chosen that the resistance value keeps rising as it becomes heated. This means that the energization of the solenoid 47 decreases more and more and the rudders are held in the hard-over position with less and less force. As the torpedo speed is still not materially diminished the spiral operation of the torpedo is obtained.

If, in spite of the spiral searching of the torpedo for the target, it still fails to make a hit, the battery will become exhausted and the propulsion motor will stop. Since the torpedo normally has a negative buoyancy, it will, under these conditions, sink and thus not become a menace to shipping generally.

While we have gone into considerable detail about the steering control system, the structural

features of our gyro are no less important but constitute an important contribution to the art.

As seen in Figs. 2 and 3, it will be noted that the gyro wheel 23 is mounted on the inner gimbal ring 60 for rotation about the spin axis falling, as near as manufacture can accomplish this in the geometric axis of the drive shaft 61 for the gyro wheel.

The left-hand end of the inner gimbal ring 60, as seen in Fig. 3, is provided with a hollow stud 62 threaded externally and threaded internally. Disposed within the stud beyond the internal threads, the outer race 63 of the ball bearings is positioned. To prevent any axial movement of the drive shaft with reference to the gimbal ring 60 the nut 64, having the sleeve extension or projection 65 shown at the right end of the nut, is driven down so that the extension firmly engages the outer ball bearing race 63. The drive shaft 61 thus has no end play toward the left.

At the right, the gimbal ring 60 has an internally threaded opening for receiving the external threads of the knurled generally cup shaped nut 66. The base of the nut 66 is provided with an opening through the sleeve-like left end of the clutch disk, or clutch cone, 67 extends. A roller bearing similar to the one at the left is positioned in the nut 66. A washer 68 is disposed directly to the right of the roller bearing. This washer has an annular left-hand projection engaging the outer race 69 of the ball bearing and an annular right-hand projection for centering the compression spring 70'. The compression spring 70' of suitable design and under a selected compression firmly positions the ball bearing so that shaft 61 has no end play in a direction toward the right.

At points directly at right angles to the spin axis the inner gimbal ring 60 is journaled in the outer gimbal ring 70. These journals are also provided with ball bearings which are firmly held against axial displacement as shown at the left in Fig. 2.

At points directly at right angles to both the spin axis and the axis of rotation of the inner gimbal ring 60 on the outer gimbal ring 70, the outer gimbal ring is journaled in the frame 71 of the gyro mechanism. This is best shown in Fig. 2. It will be noted that the annular nut 72 has an inner downwardly directed shoulder against which the outer race of the upper ball bearing 73 rests so as to prevent the possibility of any upward axial movement of the control shaft 74. At the lower journal for the gimbal ring 70 a nut 75 having an annular inner projection engaging the outer race of the ball bearing 76 prevents any downward axial movement of the control shaft.

The axis of rotation of the outer gimbal ring 70 in the frame 71 is disposed at right angles to the axis of rotation of the inner gimbal ring 60 on the outer gimbal ring 70 and also at right angles to the spin axis of the gyro wheel. The arrangement, design and care of manufacture is such that the three axes are mutually perpendicular axes intersecting at the point of the center of mass of the rotating system. This means that the gyro wheel, assuming perfect balance and assuming the conditions of intersection for the axes mentioned are satisfied, is a solid body unconstrained with reference to rotation, since the body can rotate about any one, two, or all three of the axes. Such a body if set to spin, disregarding friction torques, etc., will indefinitely

maintain its spin axis in a given direction in space.

From the foregoing, it is apparent that if a pointer were to be attached to the upper end of the control shaft 74 and the gyro wheel were spinning at a relatively high speed, any movement of the frame 71 in azimuth about the shaft 74 would in nowise affect the disposition of the pointer in space.

10 In practice, the control shaft 74 is mounted so as to be in a vertical position when the torpedo is on even keel. The depth control devices so control the travel of the torpedo that the control shaft 74 does remain in a substantially vertical position.

15 We, therefore, need merely to obtain a suitable controlling effect from the position of such hypothetical pointer at the top of shaft 74 with reference to some point on the torpedo. This control effect we obtain from the mechanisms mounted at the top of the gyrostat frame. Before we discuss these features of our invention, we must take into account at least two more factors.

20 25 It is manifestly impossible to obtain perfect balance of a rotating system merely by careful dimensioning, machining, and positioning of the parts. After our gyro wheel and the rings associated with it have been carefully balanced, it is necessary as an added precaution and an added refinement that the rotating system be rebalanced after assembly. This we accomplish by means of the balancing nut 77 disposed on the outer threads of the hollow stud 62. By carefully 30 shifting the nut axially of the stud, a position can be obtained for the nut on the stud to make the gyro wheel unconstrained with respect to rotation.

An index is then placed on the extension strip 40 78 and on the nut, so that the position of balance is indicated.

45 The other factor is one dependent on the latitude at which the torpedo is fired. Suppose the torpedo were fired from a position at latitude 90° toward a target some distance away. Since the hypothetical pointer at the top of the control shaft 74 continues to point in the same direction in space, the torpedo, if following the direction in which the pointer points, will miss the target because the target not being at latitude 90° will have moved east by an amount directly dependent upon the time it took for the torpedo to travel from latitude 90° to the latitude of the target.

50 55 At other latitudes than 90°, the discrepancy will not be as great, but nevertheless will be a function of the ratio of time to the sine of the angle of latitude.

55 60 If a force of the right magnitude and distance from the center of mass can be caused to act perpendicular to the spin axis, just the right amount of precession can be given to shaft 74 to compensate for latitude. We use the weight 77 for this purpose.

65 The weight 77, after its balance position has been fixed, is provided with graduations indicating the extent to which the nut must be moved toward the left or away from the center of mass for various degrees of latitude.

70 75 At the upper portion of the frame 71, we rotatably mount the annular member 79 on the projecting hollow stud 80. At the outer periphery of the sleeve-like extension 81, we provide gear teeth 82 for engagement with a worm on shaft 83. By means of suitable shafts carrying bevel gears as shown, the transmission is carried to the shaft

84 (see Fig. 2). The shaft 84 is disposed athwart the torpedo and the ends are provided with couplings 85 and 86, so that the annular member 79 may be angularly adjusted from either side of the torpedo. The drive to the couplings 85 and 86 may be done from the outside without the chance of any leakage into the torpedo at such points after the torpedo is fired.

Mounted on the annular member 79 is the cap 87 of insulating material. This cap has an annular projection 88 to firmly hold it on the member 79 so that it may rotate with member 79 when setting the course for the torpedo. Rigidly secured to the inner periphery of the cap are two semicircular segments 29 and 30 of conducting material separated by two relatively narrow diametrically disposed insulating strips, one of which, as 31, being shown in Figs. 1 and 2.

Connected to the upper end of the control shaft 74 is the disc-like construction 89 upon which is mounted the relatively wide and fairly rigid strap 90. To one end of strap 90 is secured the leaf-spring contact, or current-carrying member, 91. The other end of the strap is bent up at right angles to the plane of the strap. To this bent-up end is secured the contact strap 92 carrying the roller 32. Elements 90, 91, 92 and 32 in effect constitute the hypothetical pointer mentioned. This strap 92 is disposed with the edges up and down, that is, the side surfaces falling in vertical planes.

Considerable vibration occurs on a torpedo and not to subject the control to the danger of current failure at the roller 32, the strong strap 90 and the edgewise disposition of strap 92 prevent shifting of the roller 32 with reference to the segments 29 and 30 so as to have any electric circuit open at the roller.

Vibration radially of the shaft 74 is not very prevalent, besides strap 90 permits of no radial vibration of the roller 32 and strap 92 is too short and too strong to permit such vibration. Our construction thus prevents current interruption at roller 32 because of vibration.

Disposed on the frame 71 is an index 93 coacting with graduations on the conical surface 94 of the cap 87. This index 93 and the graduations on surface 94 are visible from the outside of the torpedo through a lens-like window. The disposition of the graduations is such that they indicate with reference to the index 93 the exact angle shot that is being made. In other words, if the target is disposed 37° and 30' to the right of the torpedo tube, the attendants through couplings 85 or 86 rotate the cap until 37° and 30' to the right of the zero graduation register with the index. This means the insulating strip 31 is disposed 37° and 30' to the right of the position of the point contact of roller 32 with segment 29. Then when the torpedo is fired, the steering mechanisms will turn the torpedo until the roller contacts the strip 31 at which time the torpedo is on course.

It is manifestly important that the gyro wheel and the gimbal rings be so locked in position while the gyro wheel is to be brought up to speed that the clutch disc 67 makes proper operative contact with the clutch element 100 but that the gimbal rings 60 and 70, after release of the clutch elements 67 and 100, be free to rotate.

The clutch actuating lever 20 is of the inverted Y-type pivoted at the ends of the Y. At the crotch, the lever straddles the clutch actuating spool-like sleeve 102. This sleeve is actuated toward the left by a relatively heavy spring 104 to

normally cause firm engagement of the clutch 22. When the solenoid 17 is energized, the armature 19 is actuated toward the right (see Fig. 3), and the gyro wheel is thus declutched from the gyro motor GM.

5 The lever 20 is provided with an arm 106 for coaction with the gyro locking means to prevent release of the rotating assembly before the gyro wheel is released from the motor.

10 The locking means for the rotating assembly comprises a generally H-shaped member 108 pivoted to the frame 71 at the outer ends 109 and 110 of the lower legs. The upper legs 111 and 112 are designed to straddle the outer gimbal ring 70 with a fairly close fit, so that this ring, when member 108 is in locking position, can not rotate about its trunnions in the frame. Since the gimbal ring 70 can have a right and a wrong position, it is important that it be made impossible to properly position member 108 except when the gimbal ring 70 is in the right position. To this end, we provide one quadrant of the ring with small projections, as 113, shown in Fig. 2, at each side of the ring. These projections are, when ring 70 is in the wrong position, in the path of the upper legs of the member 108. Member 108 can thus be positioned correctly to lock ring 70 only when the proper quadrant of the ring faces the upper legs of member 108.

15 The upper ends of the legs 111 and 112 are provided with projections 114 and 115. These projections carry bolts as shown. These bolts may be locked in such position that the upper ends engage the bottom side of the port side of ring 60 when this ring is in proper position.

20 The wrong side of the ring 60 is provided with projections 116 and 117 that are in the path of the upper ends of the bolts in the projections 114 and 115. Member 108, even if ring 70 be correctly positioned, can not be moved to locking position except if both rings 60 and 70 are in correct position.

25 Further, as long as member 108 is not in locking position, the arm 106 will rest on the shoulder 118 and the gyro wheel 23 can not be driven.

30 The member 108 is normally biased to move out of locking engagement by the tension spring 120 secured to member 108 and the frame. The unlocking operation, once the member 108 is in locking position, can not take place because arm 106 is then disposed in front of shoulder 118. The only way the rotary assembly can be unlocked is after the gyro wheel is up to speed and the torpedo has been fired so as to energize the solenoid 17.

35 The gyro transfer switch comprises a three-armed member 121 pivoted on a pivot transverse of the torpedo and biased by a suitable spring as shown to rotate clockwise. Such clockwise rotation can, however, not take place, except the member 108 be out of the locking position, because arm 122 rests on shoulder 123.

40 When in the position shown in Fig. 3, the gyro transfer switch is in position to close contacts 14 in the circuit of both the gyro motor GM and solenoid 17.

45 After the torpedo is fired, the trigger switch energizes solenoid 17 long enough to rapidly disengage the drive connection between the gyro motor and the gyro wheel. This time is more than ample to cause spring 120 to move the H-shaped member 108 toward the observer, as seen in Fig. 3, or counterclockwise, as seen in Fig. 2, so as to unlock the rotating system.

50 The shoulder 123 thus moves out from under

the arm 122 and in consequence the circuit for the gyro motor and for the solenoid 17 is interrupted at contacts 14. Contacts 28 are, however, closed, so that the circuit for the propulsion motor is closed.

At the same time that solenoid 17 is energized, the armature 19 causes arm 106 to move up or clockwise, so that shoulder 118 moves under the arm 106. The deenergization of solenoid 17 can thus have no further effect on the motion of clutch elements 67 and 100. These elements 67 and 100 are positively held at a considerable distance from each other by arm 106 and shoulder 118.

The gyro wheel, therefore, assumes its function of controlling the steering of the torpedo to the course set by the appropriate movement of the torpedo with reference to roller 32.

While we have shown but one embodiment of our invention, both schematically and in detail, we do not wish to be limited to the particular showing made, but wish to be limited only by the scope of the claims hereto appended.

We claim as our invention:

1. In an automatic steering control for a submersible craft, in combination, a rotatable assembly comprising, a gimbal ring disposed to rotate about a vertical axis when the craft is operating on even keel, a second gimbal ring disposed to rotate on a horizontal axis at right angles to the axis of rotation of the first gimbal ring, a gyro wheel disposed to rotate about a horizontal axis at right angles to both the other two axes of rotation mentioned; a frame for the rotatable assembly fixed to the craft, means for locking the gimbal rings against rotation, said locking means comprising a generally H-shaped lever pivoted to the frame at two of its parallel legs so that the other two parallel legs, or free legs, may straddle the outer gimbal ring to prevent it from rotating, means on the outer gimbal ring for preventing the free legs from straddling the outer gimbal ring except the outer gimbal ring be in the correct position, means on the free legs adapted to engage the inner gimbal ring to prevent it from rotating, means on the inner gimbal ring adapted to prevent locking engagement between free legs and the inner gimbal ring except the inner gimbal ring be in correct position; a motor for driving the gyro wheel; a clutch for coupling the gyro wheel to the motor; a clutch lever for actuating the clutch, said clutch lever having a part disposed to engage the flat side of the H-shaped lever to prevent unlocking of the rotatable assembly when said H-shaped lever is in position to lock the gimbal rings and when the clutch lever is in position for the clutch to couple the motor to the gyro wheel and disposed to engage the edge of the H-shaped lever when the H-shaped lever is not in locking position so that the clutch lever can not be actuated to engage the clutch once the rotatable assembly is unlocked.

2. In a steering control for a torpedo, in combination, a source of electric energy, a gyro motor adapted to be connected to the source of energy, a rotatable assembly including a gyro wheel mounted to have, when released, three degrees of freedom of rotation, the gyro wheel mounted to have a horizontal spin axis and a vertical preces-

sion axis, a clutch coupling the gyro wheel to the gyro motor, locking means for locking the rotating assembly so that the gyro wheel has but one degree of freedom of rotation namely about

5 the spin axis, adjustable means disposed for adjustment axially of the spin axis for producing a precession about the precession axis to compensate for the latitude at which the gyro wheel is used for controlling the torpedo, and means

10 responsive to the firing of the torpedo for decoupling the gyro motor from the gyro wheel and for releasing the locking means.

3. In an automatic steering control for a submersible craft, in combination, a gyrostat includ-

15 ing a gyro wheel mounted, when released, to have three degrees of freedom of rotation and disposed on the craft so that the precession axis is vertical, locking means for holding certain of the elements of the gyrostat so that the gyro wheel has but one degree of freedom of rotation namely about the spin axis, driving means for the gyro wheel, means responsive to the starting of the craft for decoupling the gyro wheel from the gyro motor and for operating said locking means to release the gyro wheel so that it has three degrees of freedom of rotation, means responsive to the position of the precession axis with reference to a selected point on the craft for controlling the steering of the craft so that the precession axis holds a selected position with reference to the selected point on the craft, and means responsive to a selected distance of travel of the craft for causing the craft to move in a spiral course.

4. In an automatic steering control for a submersible craft, in combination, a source of elec-

35 trical energy, electromagnetic steering control devices, gyroscopic means for controlling the energization of said electromagnetic devices as a function of the direction of travel of the craft with reference to a direction of travel of the craft selected by said gyroscopic means, said gyroscopic means including a gyro wheel, a gyro motor, connected to the source of energy, for driving the gyro wheel, means for locking the gyro wheel in

40 position to have one degree of freedom of rotation about a horizontal spin axis, means responsive to the starting of the craft for uncoupling the gyro wheel from the gyro motor and for un-

45 locking the gyro wheel so that it has three degrees of freedom of rotation, means responsive to the unlocking of the gyro wheel for interrupting the electrical connection of the gyro motor and source of energy.
